CLAIM

The ornamental design for a cryopreservation container, as shown and described.

DESCRIPTION

FIG. 1 is a perspective view of a cryopreservation container in accordance with Embodiment 1 of the present design;

FIG. 2 is a front view thereof;

FIG. 3 is a top view thereof;

FIG. 4 is a bottom view thereof;

FIG. 5 is a right side view thereof; and,

FIG. 6 is a perspective view of the cryopreservation container in a state of use.

The broken lines in the drawings depict environmental subject matter and form no part of the claimed design.

1 Claim, 3 Drawing Sheets
